Primary Examiner—Ralf Seifert[57] **CLAIM**

The ornamental design for an anti static key chain, as shown and described.

DESCRIPTION

FIG. 1 is a perspective view of an anti static key chain showing my new design;

FIG. 2 is a top plan view thereof;

FIG. 3 is a right side elevation view thereof, the left side elevation view being identical;

FIG. 4 is a rear elevation view thereof; and,

FIG. 5 is a front elevation view thereof.
